United States Patent

Des. 234,780
Patented Apr. 8, 1975

234,780

GAME TABLE

Robert W. Le Mieux, Spring Lake, Mich., assignor to Brunswick Corporation, Skokie, Ill.

Filed Oct. 13, 1972, Ser. No. 297,206

Term of patent 14 years

Int. Cl. D21—01

U.S. Cl. D34—5 J

FIG - 3

FIG - 4

FIG. 1 is a perspective view of a game table of my design.

FIG. 2 is an end view of the table shown in FIG. 1.

FIG. 3 is a side view of the table shown in FIG. 1.

FIG. 4 is a top view of the table shown in FIG. 1.

FIG. 5 is a cross-sectional view of a side rail and ledge of the table shown in FIG. 1.

I claim:

The ornamental design for a game table, substantially as shown and described.
